UNITED STATES PATENT OFFICE.

WHITMAN SYMMES, GEORGE H. HARMAN AND CHARLES F. DUVAL, OF SAN FRANCISCO, CALIFORNIA, ASSIGNORS TO THOMAS DAY COMPANY, OF SAN FRANCISCO, CALIFORNIA, A CORPORATION OF CALIFORNIA.

LIGHTING FIXTURE.

Application filed June 9, 1926. Serial No. 114,689.

Our invention relates to interior lighting fixtures of the type employing translucent shades, and is particularly applicable to fixtures which are pendant from the ceiling.

5 An object of our invention is to provide a lighting fixture in which a screen is used for preventing the source of light from being seen thru the open end of the shade.

10 Another object of our invention is to provide a lighting fixture in which the means for supporting the screen does not cast objectionable shadows.

15 Another object of our invention is to provide a lighting fixture in which the screen will permit light reflected by the shade to pass thru the open end of the shade.

20 A further object of our invention is to provide a lighting fixture in which the shade and the ceiling are directly illuminated.

25 The invention possesses other advantageous features, some of which with the foregoing, will be set forth at length in the following description where we shall outline in full that form of the lighting fixture of 30 our invention which we have selected for illustration in the drawing accompanying and forming part of the present specification. In said drawing we have shown one form of lighting fixture embodying our invention but it is to be understood that we do not limit ourselves to such form since the invention as set forth in the claims may be embodied in a plurality of forms.

35 In the drawing:

35 The figure shows a lighting fixture embodying our invention, the left half being in section and the right half being in elevation with a portion of the shade removed from the frame.

40 Various features of the lighting fixture of our invention which are shown in the accompanying drawing, but which are not claimed herein, are claimed in our co-pending application entitled "Chandelier," Serial No. 114,688, filed June 9, 1926.

45 Broadly speaking, our invention comprises a lighting fixture having a shade with an open end and which is provided with a screen to shield the source of light from 50 view thru the open end, the screen being so supported that the shadow of the support falls on an opaque portion of the shade. Our lighting fixture is preferably hung

from the ceiling 3 by means of a chain 4 which is suitably fastened thereto and which is embellished at its point of attachment to the ceiling by an ornament 6. At the lower end of the chain 4 a tube 7 is fastened and carries at its lower end an electric socket 8 of the standard type. An electric globe 9 is screwed into the socket and is supplied with electricity by means of wires (not shown) which depend from the ceiling and may be intertwined with the chain 4.

55 A suitable shade 11, preferably of translucent material and generally either of parchment or silk is provided for the electric globe 9 and is reinforced at its edges by being mounted upon suitable stiff hoops or wire rims 12 and 13 spaced by bars 14. The shape of the shade can be of any of the usual forms and in the present instance is approximately a circular cylinder. It is very desirable to make the shade detachable from the remainder of the lighting fixture so that the fixture can first be installed and properly positioned and then the comparatively delicate shade can be put on. It is also sometimes a requisite that the shade be easily removable for cleaning or renewal. To afford the translucent shade 11 a firm support and yet render it readily removable from the balance of the fixture, radial arms 16 are provided which are suitably fastened at their outer ends to the top rim 13. The 65 arms 16 extend radially toward the light globe 9 and then are bent to lie parallel with the tube 7. The upper ends of the arms 16 are then bent back to form hooks. A suitably apertured disc 17 is mounted between jam nuts 18 and 19 suitably engaging the lower threaded end of the tube 7. The 70 hooked ends of the arms 16 are hooked into the apertures in the disc 17, and may readily be removed therefrom by lifting the entire shade 11. By suitably adjusting the jam nuts 18 and 19, the disc 17 may be moved axially of the tube 7 to adjust the 75 position of the shade 11 with respect to the light globe 9.

80 In order to prevent the hooked ends of the radial arms 16 from accidentally becoming disengaged from the disc 17, means are provided for retaining them firmly in place. These means preferably comprise a hood or 85 ornamental husk 21 which is slidably mount- 90

ed upon the tube 7 and which can be positioned along the tube 7 so that it overlies closely or bears against the parallel portions and the hooked ends of the arms 16. The 5 hood 21 is maintained in place by means of a collar 22 provided with a set screw which may be engaged with the tube 7. By sliding the collar 22 into close engagement with the hood 21 and subsequently tightening the set screw, the entire assembly may be held in quite rigid relationship, but is easily disassembled by loosening the collar and sliding the hood 21 upwardly on the tube, thereby releasing the hooked ends of 10 the arms 16.

Means are provided for preventing the source of light from being visible from below the lighting fixture and preferably comprise a non-transparent screen 23. The 15 screen 23 is usually in the form of a disc or plate which may be translucent or quite opaque whichever is best adapted to the particular conditions affecting the lighting fixture. The contour of the screen should 20 be similar to the shape of the shade. In the present instance the screen is a circular disc of glass having an irregular surface. The disc or plate 23 is supported by a ring 24 made of a suitable metal angle which in 25 turn rests on depending hangers 26. The ring 24 and the hangers 26 are preferably joined at their points of contact as by soldering or brazing to form a unitary structure. The upper ends of the hangers 26 30 are bent over to form hooks which engage the radial arms 16. The hooks preferably fit loosely over the radial arms so that the entire screen structure, including the hangers 26 and the ring 24, may be lifted slightly, rotated and then dropped to remove it 35 from the remainder of the lighting fixture.

It is desired that light rays may be reflected from the interior of the shade and pass out of the lower end of the fixture. 40 This is preferably accomplished by spacing the screen 23 an appreciable amount above the bottom of the shade thereby allowing ample room for the reflected light rays to leave the lower end of the shade. A typical reflected light ray is indicated by the broken line A in the drawing.

It is also desired to position the supporting ring 24 for the screen 23 in such a manner that the shadow which it casts will not 45 fall upon the shade 11 and be objectionably apparent. The supporting ring 24 and the

hangers 26 which hold it in place are preferably so proportioned with respect to the size of the plate 23 that the opaque ring 24 and the edge of the plate 23 are substantially in alinement with the lower opaque rim 12 of the shade and the source of light 27. The various parts of the fixture can be made and assembled so that the lower rim 12 of the shade 11 and the opaque support of the 50 screen 23 are approximately in alinement with the source of light and then the disc 17 may be manipulated to raise or lower the shade and screen until their opaque portions are in perfect alinement with the source of 55 light. No objectionable shadows are then cast on the shade by the ring 24 supporting the screen which renders the source of light invisible from below the fixture. The light rays emanating from the source of light 60 fall directly upon the shade 11, directly upon the ceiling and upon the screen 23. An even illumination is produced without objectionable shadows on the shade.

We claim:

1. A lighting fixture comprising a source of light, a substantially cylindrical shade surrounding said source of light, an opaque rim on said shade, a screen for rendering said source of light invisible thru an open 85 end of said shade, and an opaque rim on said screen, said second-named rim casting a shadow substantially entirely on said first-named rim.

2. A lighting fixture comprising a source 90 of light, a shade surrounding said source of light and having an open portion, an opaque rim around said open portion, a screen for rendering said source of light invisible thru said open portion, and an 95 opaque portion on said screen, the shadow of said opaque portion being cast substantially entirely on said rim.

3. A lighting fixture comprising a source of light, a substantially cylindrical shade 100 coaxial with said source of light, an opaque rim around the bottom of said shade, a non-transparent circular plate coaxial with said shade and spaced above the bottom of said shade so that the edge of said plate is in 105 alinement with said rim and said source of light.

In testimony whereof, we have hereunto set our hands.

WHITMAN SYMMES.
